CLAIM

The ornamental design for a display screen with graphical user interface for compliance prediction software program, as shown and described.

DESCRIPTION

The FIGURE is a screen image of a display screen with a graphical user interface for a compliance prediction software program.

The outermost broken line rectangle shows the display screen, and forms no part of the claimed design. The broken line bars and broken line box in the bar graph element form part of the claimed design. All other broken lines in the FIGURE show portions of the graphical user interface and form no part of the claimed design.
